US00D536038S

(12) United States Design Patent (10) Patent No.: US D536,038 S
(45) Date of Patent: * Jan. 30, 2007

(54) LABEL FOR PACKAGING

(75) Inventors: Mattias Frendberg, Göteborg (SE);
Branko Schreurs, Göteborg (SE);
Mikael Schultz, Lerum (SE)

(73) Assignee: Astra Tech AB, Molndal (SE)

() Term: 14 Years

(21) Appl. No.: 29/224,287

(22) Filed: Mar. 1, 2005

(Under 37 CFR 1.47)

(30) Foreign Application Priority Data

Sep. 3, 2004 (EM) 000223524

(51) LOC (8) Cl. 19-08

(52) U.S. Cl. D20/27

(58) Field of Classification Search D20/10,
D20/11, 22, 23, 26, 27, 29, 34, 40, 41, 42,
D20/99; D5/8, 56; D9/414, 432; 40/124.01,
40/312; 283/56

See application file for complete search history.

(57) CLAIM

The ornamental design for a label for packaging, as shown and described.

DESCRIPTION

The patent or application file contains at least one drawing executed in color. Copies of this patent or patent application publication with color drawing(s) will be provided by the office upon request and payment of the necessary fee.

FIG. 1 is a front view of a label for packaging showing our new design;

FIG. 2 is a perspective view thereof;

FIG. 3 is a front view of a second embodiment of a label for packaging showing our new design;

FIG. 4 is perspective view thereof;

FIG. 5 is a front view of a third embodiment of a label for packaging showing our new design; and,

FIG. 6 is perspective view thereof.

The dotted line showing is for environmental purposes and is not part of the claimed design.
